UNITED STATES PATENT OFFICE.

TAYLOR W. HEINTZELMAN, OF SACRAMENTO, CALIFORNIA.

SAFETY CHECK-VALVE FOR STEAM-BOILERS.

SPECIFICATION forming part of Letters Patent No. 538,831, dated May 7, 1895.

Application filed March 4, 1895. Serial No. 540,484. (No model.)

To all whom it may concern:

Be it known that I, TAYLOR W. HEINTZELMAN, of Sacramento, in the county of Sacramento and State of California, have invented 5 a certain new and useful Improvement in Safety Check-Valves for Steam-Boilers, of which improvement the following is a specification.

My invention relates to the type or class of 10 boiler feed appliances, embodying a main check valve, located outside of the boiler, and a second or supplemental check valve having direct communication therewith, and located inside of the boiler; the construction 15 being such that in the event of the main or outside valve being removed or broken off, the inner or supplemental check valve will prevent the escape of water or steam, and thereby obviate the liability to accident resulting therefrom.

The object of my invention is to provide a 20 valvular device of simple and inexpensive construction, and capable of application in the ordinary manner, all of whose parts, especially such as are subject to wear in ordinary usage, shall be readily accessible without the necessity of removing the entire device from the boiler.

A further object of my invention is to obviate liability to imperfect operation of the 25 valves, by the accumulation of sediment or scale, on or around their seats.

The improvement claimed is hereinafter fully set forth.

30 In the accompanying drawings, Figure 1 is a vertical central section through a safety check-valve device embodying my invention in operative position on a boiler; Fig. 2, a transverse section at the line $x-x$ of Fig. 1; 35 and Fig. 3 a similar section at the line $y-y$ of Fig. 1, showing the arrangement of ports in the inner end of the valve casing.

In the practice of my invention I provide a 40 spherical main valve casing 1, which is provided with a horizontally projecting cylindrical portion 2, which is externally threaded for connection with the outer end of a cylindrical supplemental valve casing 3, adapted to be inserted in, and in operative position, 45 project into, a steam boiler or other receptacle

of fluid under pressure, to which fluid is to be supplied. The valve casing 3 is connected to the shell 4 of the boiler, by tap bolts 5, passing through holes in a flange 6, formed on the outer end of the casing 3. A ring 7, having 55 a face turned to the form of a segment of a sphere, and fitting in a correspondingly bored recess in the boiler shell, is preferably interposed between the latter and the flange 6, to insure a tight joint having a certain degree 60 of flexibility. The feed pipe 8, through which water is forced by means of an injector or pump to the valve casings, is connected by means of an ordinary union joint, to a tubular elbow portion 9, formed integral with the 65 lower side of the spherical main valve casing 1.

The upper end of the elbow 9, extends a short distance into the valve casing 1, and has its inner diameter slightly contracted, at its 70 upper end, in order to form a seat for the main valve 10, which is of the puppet or lift type, and is forced against said seat, thus cutting off the flow of fluid through the same, when the pressure in the boiler exceeds that 75 in the feed pipe 8.

The main valve 10 is provided with a downwardly projecting stem 11, which slides in a vertical guide 12, which is formed integral with the inner wall of the elbow 9, and is located 80 in such position as to offer the least practicable impediment to the flow of fluid through said elbow.

The main valve 10 is provided, on its top, 85 with wings 13, which project radially from its axial line, and are turned to slide in a cylindrical guide 14, located near the top of the spherical main valve casing 1, said guide 14 being connected, by means of radial arms 15, to the inner side of a screw cap 16, which is 90 fitted to screw into the top of said casing 1, in order to permit of the main valve 10 being removed without disconnecting the feed pipe 8. The radial arms 15 also serve as a stop to prevent the valve 10 being raised too far from 95 its seat. As will be readily seen, the guides 12 and 14, together with the guide stem 11 and wings 13, will maintain the valve 10 in proper position, and prevent any lateral displacement which might occur if a guide stem only 100

were used. It will be obvious that, if preferred, a central stem may be substituted for the wings 13, and will similarly perform the function thereof.

5 The valve seat and main valve 10, are encircled by a shield or guard 17, which is formed integral with the valve casing 1, and extends upwardly therein a sufficient distance to surround the main valve 10, when it is raised to 10 the limit of its lift. The shield or guard is of greater diameter than the valve seat, and forms the outer boundary of an annular recess or chamber surrounding it, which receives sediment or deposit which would otherwise 15 tend to lodge on the valve seat. The shield 17 serves to prevent the formation of scale, due to the use of impure water, around the main valve 10, or its seat, thus allowing said valve to become properly seated, when the 20 pressure in the feed pipe 8 is reduced, and preventing any leakage, as would be the case if scale were allowed to collect upon the main valve 10 or its seat.

The supplemental check valve 18, which is 25 also of the puppet or lift type, is fitted to reciprocate, horizontally within the boiler, in the supplemental valve casing 3, and prevents the outward flow of fluid through the same, when forced by the pressure in the boiler against a 30 seat 19, which is shown as about in line with the inner surface of the boiler shell, but which may be located in any desired position substantially within, or on the inner or delivery side of, the plane in which the casing bears 35 against the boiler shell. The valve 18 is guided in its movements by longitudinal ribs or projections 20, formed integral with wings 21, projecting radially from its stem, said ribs or projections being turned to slide in the supplemental valve casing 3.

The valve 18 is limited in its movement by a stop 22, formed upon the inner face of a screw cap 23, fitted to screw into the inner end of the supplemental valve casing 3, thus permitting 45 the insertion in position of the valve 18, and ready access thereto for the purpose of renewal or repair. Water fed to the valve casings by the injector or pump, is delivered from the casing to the interior of the boiler 50 through a series of circumferential ports or openings 24, formed in the supplemental valve casing 3, on the inner or delivery side of the valve seat 19.

In the operation of the appliance, both the 55 valves 10 and 18, are normally held seated, by the pressure in the boiler, during the periods in which water is not being fed to the boiler. When the injector or pump is started, the water which is thereby forced into the elbow 60 portions 9 below the main valve 10, unseats said valve and fills the spherical valve casing 1 and horizontal projection 2, and bears against the supplemental valve 18. The pressure of the entering water then unseats 65 the supplemental valve 18, and the water is

delivered to the interior of the boiler through the longitudinal openings 24, in all directions except directly against the tubes, thereby tending to obviate the formation of scale or incrustation at or near the valve seats. 70 The circular shield 17, around the main valve 10, also serves as a trap to prevent incrustation around the said valve. Upon the reduction of external pressure, by the cessation of the action of the injector or feed 75 pump, or the rupture of the feed pipe, the pressure in the boiler instantly closes the two check valves 18 and 10, the operation of both valves, in opening and closing being practically simultaneous. 80

If it is desired to remove the main valve 10 for the purpose of regrinding or for any other reason, it can be easily accomplished by removing the screw cap 16, thus exposing the interior of the spherical valve casing 1, and 85 rendering all parts of said casing accessible for cleaning, repairs, &c., the supplemental valve 18, meanwhile, remaining closed, to prevent escape of water or steam. The supplemental valve 18 may be reground without 90 removal from the boiler by detaching the main or outer casing 1, and inserting a suitable tool in the then open end of the supplemental valve casing 3. In case of any damage to the feed pipe or main valve, or even 95 should the feed pipe and main valve be entirely broken off, which breakage might occur between the main check valve 10 and the boiler, the supplementary valve 18 would be unaffected and would perform the function 100 of preventing the escape of hot water and steam from the boiler, thus obviating danger of injury resultant thereon.

I claim as my invention and desire to secure by Letters Patent—

1. In a safety check valve appliance, the combination, substantially as set forth, of a main valve casing having tubular connections for a feed pipe and for a supplemental valve casing respectively, a supplemental valve casing connected thereto and adapted to be secured to and project within a boiler shell, a main check valve seating in the main casing, a removable cap secured to said casing and closing an opening therein for the insertion and removal of the main check valve, a guide on said cap fitting wings on one side of the main valve, a guide on the main casing fitting a stem on the opposite side of the valve, and a supplemental check valve working in the supplemental casing and controlling communication between said casing and the boiler through a series of circumferential ports or openings in said casing. 110 115 120

2. In a safety check valve appliance, the combination, substantially as set forth, of a main valve casing having tubular connections for a feed pipe and for a supplemental valve casing respectively, a supplemental valve casing connected thereto and adapted 125 130 135

to be secured to and project within a boiler shell, a main check valve seating in the main casing, a shield or guard surrounding and extending above the valve seat, and a supplemental check valve working in the supplemental casing and controlling communication between said casing and the boiler through a series of circumferential ports or openings in said casing.
